PLUG BUTTON OR CLOSURE

Philip D. Becker, Hingham, Mass., assignor to
United-Carr Fastener Corporation, Cambridge,
Mass., a corporation of Massachusetts

Application November 17, 1948, Serial No. 60,497

9 Claims. (Cl. 220—60)

1

The present invention relates to plug buttons and like closures for apertured members, for example apertured metal supports, and aims generally to improve the construction of existing plug buttons and like closures.

A primary object of the invention is the provision of an improved plug button adapted to be positioned in an apertured support and which will have an improved locking or gripping action with a wall of a support aperture.

A further object of the invention is the provision of an improved plug button adapted for attachment to supports of varying thickness.

A still further object of the invention is the provision of an improved plug button that may be readily manufactured to fit an opening of predetermined size and which will substantially resist forces tending to distort it from its initial size and shape, such as may be encountered in shipment and handling.

The above and other objects of the invention will be apparent to persons skilled in the art to which the invention relates from a consideration of the accompanying drawings and annexed specification, illustrating and describing a preferred embodiment of the invention.

In the drawings:

Fig. 1 is a top plan view of a plug button as applied to an apertured support;

Fig. 2 is a side elevation of the plug button shown in Fig. 1;

Fig. 3 is an enlarged vertical sectional view of a plug button embodying the invention as taken on the line 3—3 of Fig. 1; and

Fig. 4 is an enlarged bottom plan view of the plug button shown in Fig. 3.

Referring to the drawings, the improved plug button is preferably of two-part construction comprising an attaching or fastener part 10 and a cap member 20 which may be a closure part overlying the attaching member.

The attaching or fastener part 10 comprises an annulus 11, preferably of one-piece and continuous construction, and provided with a circular series of spaced radially-extending support-engaging tongues 12 projecting radially outwardly from the outer peripheral edge of the annulus. The annulus 11 is further provided with a circular series of radially and outwardly extending connecting arms 13, preferably arranged intermediate the tongues 12, each of which terminates in segmental strips 14 adapted collectively to form a cap-carrying annulus disposed in a plane spaced from the annulus 11. As illustrated in Fig. 3, the segments 14 are disposed in a common plane, 55

2

therein illustrated as horizontal, but are angularly disposed with reference to the downwardly and inwardly inclined arms 13, so that the arms may extend within the aperture 5 of the support 6, and the segments 14 will overlie the marginal edge of the support 6 surrounding the aperture 5.

The annulus 11 and support-engaging tongues 12 are preferably disposed obliquely to the planes of the segments 14 and arms 13 so that the annulus defines an inwardly tapering entering nose for the attaching member. The support-engaging tongues thus present sharp support-engaging contact edges 12a disposed in a plane outwardly of the annulus 11. This provides for secure edge-biting engagement between the tongues 12 and the wall of the aperture 5, and the thickness of the support 6 may vary considerably as will be apparent, by comparing the supports illustrated at the right and left hand sides of Fig. 3.

20 The segments 14, providing the cap-supporting annulus, are preferably of sufficient length as to have abutting edges 15 to resist displacement of the segments radially inwardly during the cap or closure-attaching operations. These abutting segments 14 thus present a complete annulus of predetermined size and shape and an undistortable support for the cap or closure 20.

The cap or closure 20 may be of any suitable sheet material, for example, sheet metal or sheet plastic, having a central body portion 21, herein illustrated as arched or dome shaped, and a peripheral marginal edge portion crimped or clenched, as at 22, over and around the outer peripheral edges of the annulus formed by the segments 14. The body portion 21 may be of any desired form such as a screen or a lamp bulb lens or glass.

From the above it will be seen that the attaching or fastening member 10 may be readily blanked and stamped as of single piece construction from a body of suitable resilient sheet material, for example sheet metal. The cap or closure 20 may then be applied to the preformed attaching member in a second operation, as will be understood in the art.

It will be apparent that the relatively stiff tongues 12 extend toward the cap from their supporting annulus and have support-biting edges at their terminal ends which tend to bite into the support aperture wall and secure the plug button more securely thereto as force is applied to remove the button from the support. In the preferred form of the invention, the annulus 11 is radially rigid.

Although I have illustrated and described a

preferred form of the invention, I do not intend to be limited thereby as the scope of the invention is best defined in the appended claims.

I claim:

1. A plug button or closure adapted for attachment to an apertured support, comprising an attaching member having axially spaced annular tongue-supporting and cap-supporting means, a circumferential series of straight strips integrally connecting said annular means, a circumferential series of support-engaging tongues on said first named supporting means and extending therefrom angularly toward said second named supporting means, and a cap overlying and secured to said second named supporting means.

2. A plug button or closure adapted for attachment to an apertured support, comprising an attaching member having axially spaced annular tongue-supporting and cap-supporting means, a circumferential series of straight strips integrally connecting said annular means, a circumferential series of support-engaging tongues connected to and extending radially outwardly from said first named supporting means and extending therefrom angularly toward said second named supporting means, and a cap overlying and secured to said second named supporting means.

3. A plug button or closure adapted for attachment to an apertured support, comprising an attaching member having axially spaced annular tongue-supporting means and cap-supporting means, a circumferential series of straight strips integrally connecting said annular means, a circumferential series of short stiff straight support-engaging tongues extending radially and outwardly from said first named supporting means and extending therefrom angularly toward said second named supporting means, and a cap overlying and secured to said second named supporting means.

4. A plug button or closure adapted for attachment to an apertured support, comprising an attaching member having axially spaced annular tongue-supporting means and cap-supporting means, a circumferential series of straight strips integrally connecting said annular means, a circumferential series of short stiff straight support-engaging tongues extending radially and outwardly from said first named supporting means and extending therefrom angularly toward said second named supporting means, and a cap overlying and secured to said second named supporting means, said tongues having sharp terminal support-engaging edges.

5. A plug button or closure adapted for attach-

ment to an apertured support, comprising a continuous annular member, circumferentially spaced struts extending angularly from said member, a segmental portion extending laterally in opposite directions from an outer end of each of said struts; said segmental portions being adapted collectively to form a substantially annular cap-supporting member, a cap secured to and overlying said cap-supporting member, and support-engaging fastener members secured to said first named annular member.

6. A plug button or closure as defined in claim 5 characterized in that the segmental portions have abutting end edges to restrain movement of said segments and struts.

7. A plug button or closure as defined in claim 5 characterized in that the support-engaging fastener members extend obliquely from the continuous annular member toward the cap-supporting member.

8. A plug button or closure as defined in claim 5 characterized in that the support-engaging fastener members extend obliquely from the continuous annular member toward the cap-supporting member, and are provided at their terminal ends with relatively short support-gripping edges.

9. A plug button or closure adapted for attachment to an apertured support comprising a continuous annular member adapted to enter a support aperture, circumferentially spaced arms extending angularly from said member, outwardly turned flanged portions at the ends of said arms adapted collectively to form a cap-supporting member, a cap secured to and overlying said cap-supporting member, and a plurality of circumferentially spaced support-engaging fastener members integrally secured to said annular member and extending angularly outward therefrom toward said cap-supporting member.
